UNITED STATES PATENT OFFICE.

WALTER H. SMITH, OF PITTSBURGH, PENNSYLVANIA, ASSIGNOR TO MILLER SAW-TRIMMER COMPANY, OF PITTSBURGH, PENNSYLVANIA, A CORPORATION OF PENNSYLVANIA.

THROW-OUT DEVICE.

Application filed April 14, 1921, Serial No. 461,306. Renewed August 4, 1924.

To all whom it may concern:

Be it known that I, WALTER H. SMITH, a subject of the King of Great Britain, residing at Pittsburgh, in the county of Allegheny and State of Pennsylvania, have invented new and useful Improvements in Throw-Out Devices, of which the following is a specification.

My invention pertains to throw-out devices for printing presses, that is to say to mechanisms for automatically causing the elements of the printing couple to be thrown out of operative relation when a sheet is not fed to the impression element of such couple.

It is an object of my invention to provide an automatic throw-out device which will be an advance over such devices as heretofore proposed in providing an improved certainty of action. Another object of my invention lies in the production of a throw-out device which will be of an especially simple construction and easy to maintain by mechanically unskilled operators. It is another object of my invention to provide a throw-out device of such a nature that it may be applied to existing forms of press without material modification of the latter, and without interference with the usual hand or foot operated devices for throwing off the impression. And other and further objects of my invention will appear from the following description taken in connection with the claims annexed thereto.

By way of example, I have described in the following specification, and shown in the accompanying drawings, an embodiment of my invention as applied to a well known type of cylinder press and as associated with a press feeding device such as is disclosed in my co-pending application Se. No. 460,243, filed April 11, 1921. I wish it especially understood, however, that my invention can be embodied in other forms, and employed in other relations, and that changes may be made in the particular form herein described and shown, without exceeding the scope thereof, as defined in the appended claims.

In the drawings:

Fig. 1 is a side elevation of a portion of a cylinder press, having an automatic

throw-out device constructed in accordance with my invention, applied thereto;

Fig. 2 is a section, on an enlarged scale, taken on the line 2—2 of Fig. 1, looking in the direction of the arrows;

Fig. 3 is a sectional side view showing the sheet-feeler in the position it assumes when a sheet is not present on the feed-board of the press, the section being taken on the line 3—3 of Fig. 2, looking in the direction of the arrows;

Fig. 4 is a view similar to Fig. 3, but showing the sheet-feeler, in full lines, in the position it occupies when a sheet is present on the feed-board, and, in dotted lines in the position to which it is subsequently raised;

Fig. 5 is a perspective view showing some of the interacting parts by which the sheet-feeler controls the actuation of the throw-out device;

Fig. 6 is a perspective view of the actuating toggle, and associated parts, in their neutral position; and

Fig. 7 is a partial side elevation showing the positions which these parts, after being actuated, will occupy when a sheet is not fed to the feed-board.

Referring now to the drawings, 10 designates the side frame of a cylinder press, the impression cylinder being indicated at 11. In such a press, it is common to provide a foot lever 12, having a treadle 13, by the operation of which the bed and impression cylinder are thrown out of cooperative relation whenever the operator desires to throw off the impression. By the mechanism hereinafter to be described, this foot lever 12 is actuated automatically whenever a sheet is not fed into position to be received by the cylinder 11.

The press is illustrated as equipped with a feed device of the kind disclosed in my co-pending application above referred to, such feed device including a framework 14 carrying a transverse shaft 15, driven from the press. The feed device also includes a feed-board 16 which terminates in a feed-plate 17, and has secured thereto a pair of tracks 18. On the forward ends of the tracks 18 are mounted bearing brackets 19 which carry a transverse rod 20 extending across the feed-plate 17 somewhat to the

rear of the front edge thereof. On this rod 20, adjacent the center of the feed-plate 17, is mounted the feeler device which controls the actuation of the throw-out mechanism.

Suitably pivoted, at 21 (Figs. 1, 2 and 6), with respect to the framework 14, is a lever 22 having a cam roll 23 which cooperates with a cam 24, mounted on the shaft 15 to rotate with the latter. Connected with the free end of the cam lever 22 is a link 25 which slides in a bearing 26 carried by the press frame 10. The link 25 is connected, through the intermediary of a slideable rod 27, with a stop bar 28. A compression spring 29 is provided on the slideable rod 27, so that, in normal circumstances, a forward movement of the link 25 will effect a like forward movement of the stop bar 28, but when the stop bar 28 is prevented from moving forward, the spring 29 will be compressed, allowing the link 25 to move towards the then stationary stop bar. The stop bar 28 is guided, from above, by a lug 30 extending from a bracket 31 secured to the press frame 10. It is guided from below by a grooved roller 32 carried by a vertically movable spring-pressed pin 33 mounted in the front end of the bracket 31. The stop bar 28 is formed, at its end, with a depressed portion 34 terminating in a shoulder 35. Upon this depressed portion 34 normally rests a roller 36 carried by a stem 37 which extends downward from an arm 38 mounted on a shaft 39 which is rockably supported in the bracket 19, a spring 39^a being provided for returning the shaft to its original position after being rocked. On its lower side, the stop bar 28 is formed with a shoulder 40, which normally clears a lug 41 formed on the bracket 31, but which will engage the lug 41 when the stop bar is depressed. Pivoted respectively to the link 25 and the stop bar 28 are toggle links 42 and 43, their other ends being pivoted to a rod 44 which passes through the foot lever 12, and has a collar 45 thereon, so that a depression of the rod 44 will cause a like depression of the foot lever 12, and thus effect a throwing off of the impression.

Normally, when the link 25 is moved forward by the action of the cam 24 on the lever 22, the stop bar 28 will likewise move forward, being maintained, by the spring-pressed roll 32, in a plane in which its shoulder 40 passes above the lug 41. During such forward movement of the stop bar 28, the stem 37 is raised, owing to the cam action of the shoulder 35 on the roller 36, the shaft 39 rocking in its bearings, which it can do in the normal condition of there being a sheet in position for being received by the impression member. When a sheet is not in a position to be received by the im-

pression member, a device to be described below prevents the shaft 39 from rocking, and thus the stem 37 from rising. Under these conditions, the shoulder 35, engaging against the roller 36, causes the stop bar 28 to be forced downward, the roller 32 being likewise forced downward against the action of the spring on its pin 33. In this lowered position of the stop bar 28, its shoulder 40 will engage against the lug 41, after which the stop bar can move no further forward. The stop bar thus being held stationary, the further forward movement of the link 25 will cause the rod 27 to slide, the spring 29 being compressed, and will cause the toggle links 42, 43 to approach each other (Fig. 7), whereby the rod 44 is forced downward and the foot lever 12 actuated, the impression being thus thrown off.

The device for locking the shaft 39 against movement when a sheet is not in position to be received by the impression member, includes a member 46 (Figs. 2-5) secured upon the rod 20 and having extending rearwardly therefrom an arm 47 which provides a bearing for the rock shaft 39. Upon the rock shaft 39 is secured a hook lever 48 having, at its end, a transversely extending hook projection 49, which extends over a shoulder 50 formed on the member 46, and beneath an abutment 51, which extends forwardly from such member. The member 46 is formed with a downward extension 52 to which is pivoted a feeler-arm 53 having, at its upper end, a hook 54 adapted, in one position of the parts, to enter between the hook projection 49 of the lever 48 and the shoulder 50 of the member 46. The feeler-arm 53 has an extending therefrom a feeler finger 55 disposed with its end above a slot 56 formed in the feed-plate 17, so that the feeler finger will enter said slot when no sheet is present on the feed-plate. When the feeler-finger thus enters the slot 56, the upper end of the feeler-arm 53 rests against an adjusting screw 57 carried by the member 46, the hook 54 being then between the hook projection 49 of the hook lever 48 and the shoulder 50 of the member 46 (Figs. 3 and 5). When a sheet is present on the feed-plate 17, as indicated at 58 in Fig. 4, the feeler-finger 55 cannot enter the slot 56, but rests on the sheet. Under these conditions, the hook 54 of the feeler-arm 53 is maintained to the rear of the hook projection 49, which latter has a bevelled rear face 59 which operates on the hook 54 to push the feeler-arm 53 still further backward when the hook lever 48 is moved downward (dotted lines Fig. 4).

The timing of the parts is such that the stop bar 28, by means of its shoulder 35, makes its attempt to raise the stem 37,

and thus rock the shaft 39, at a time when a sheet ought to be in place on the feed-plate 17, ready to be received by the impression cylinder. If a sheet is thus in place, the feeler-arm 53 will be in the position shown in Fig. 4, and there will be no impediment to the shaft 39 being rocked. Such rocking movement of the shaft 39 will shift the feeler-arm 53 and feeler-finger 55 into the position shown in dotted lines in Fig. 4, thus removing any resistance to movement of the sheet, such, for instance, as might be desired for registering. If, however, a sheet should not be present on the feed-plate 17, the feeler-finger 55 will drop into the slot 56 and the feeler-arm will fall forward into the position shown in Figs. 3 and 5, with its hook 54 beneath the hook projection 49 of the hook lever 48. Under these conditions, the engagement of the hook projection 49 against the hook 54 prevents any rocking movement of the shaft 39, the effect being that the stop bar 28 is forced into the lower plane of movement wherein its shoulder 40 engages the lug 41, and the throw-out foot lever 12 is actuated, as above explained.

An advantage of the device lies in its extreme simplicity and in its certainty of operation. Another advantage is that the mechanism does not in any way interfere with the ordinary actuation of the lever 12 by the foot treadle 13. It is to be noted, further, that no removal of parts is needed to enable the front part of the feed-board 16 to be swung upward to give access to the press cylinder, the roll 36 then leaving the stop bar 28. With the front part of the feed board thus swung upward, the automatic throw-out device will be ineffective, the lever 12, however, being operable by the foot as usual. Having thus fully described my said invention, what I claim as new, and desire to secure by Letters Patent, is:

1. In a sheet-controlled throw-out device, an element movable as a whole and having a portion adapted to move in another direction when movement of said element is prevented, a throw-out actuating member connected with said portion, an abutment normally out of the path of said element, means for moving said element, and sheet-controlled means either permitting normal movement of said element or causing it to move in a path wherein it will engage said abutment.

2. In a sheet-controlled throw-out device, a pair of toggle links normally movable together, a throw-out actuating member connected with said links so as to be moved when one of said links moves relatively to the other, means for moving one of said links, and sheet-controlled means permitting or preventing movement of the other link.

3. In a sheet-controlled throw-out device,

a pair of toggle links normally movable together, a throw-out actuating member connected with said links so as to be moved when said links move relatively to each other, means for moving one of said links, and sheet-controlled means for causing the presence or absence of an obstruction to the movement of the other link.

4. In a sheet-controlled throw-out device, a pair of toggle links normally movable together, a throw-out actuating member connected with said links so as to be moved when said links move relatively to each other, means for moving one of said links, an abutment normally out of the path of the other link, and sheet-controlled means either permitting normal movement of said other link or causing said other link to move in a path wherein it will engage said abutment.

5. In a sheet-controlled throw-out device, an element including a pair of connected members and resilient means normally maintaining said members in fixed relation with each other so as to move together, a throw-out actuating member connected with said element so as to be moved when the members of the latter move relatively to each other, moving means connected to one side of said element, an abutment at the other side of said element and normally out of the path thereof, and sheet-controlled means either permitting normal movement of said element or causing it to move in a path wherein it will engage said abutment.

6. In a sheet-controlled throw-out device, a pair of rods, a pair of links connecting the ends of said rods, resilient means normally holding said rods in fixed relation with each other, means for reciprocating one of said rods, an abutment, means for normally guiding the other rod in a path in which it will clear said abutment, sheet-controlled means for maintaining said guiding means or shifting said guiding means into a position in which said other rod will engage said abutment, and a throw-out actuating member connected with said links.

7. In a throw-out device for printing presses, an abutment, a movable slide, a resilient support normally guiding said slide in a path to clear said abutment, a throw-out actuating member governed in its operation by the engagement or non-engagement of said slide with said abutment, and sheet-controlled means either permitting normal movement of said slide or moving said support so as to cause said slide to move in a path in which it will engage said abutment.

8. In a throw-out device for printing presses, an abutment, a movable slide, a resilient support normally guiding said slide in a path in which it will clear said abutment, a throw-out actuating member associated with said slide and operated when said slide engages said abutment, and sheet-

controlled means for moving said support, to cause said slide to move in a path in which it will engage said abutment, when a sheet is not fed to the press.

- 5 9. In a throw-out device, an abutment, a movable slide having a cam projection thereon, resilient means for guiding said slide in a path in which it will clear said abutment, a member disposed in the path 10 of said cam projection and adapted, when held stationary, to force said slide downward so as to engage said abutment, a throw-out actuating member governed in its operation by the engagement or non-engagement 15 of said slide with said abutment, and sheet-controlled means either permitting movement of said first-named member or holding it stationary.

- 10 10. In a throw-out device for printing presses, an abutment, a movable slide having a cam projection thereon, resilient means for guiding said slide in a path in which it will clear said abutment, a normally movable member disposed in the path of said 15 cam projection and adapted, when held stationary, to move said slide into a path in which it will engage said abutment, a throw-out actuating member associated with said slide and operated when said slide engages said abutment, and sheet-controlled 20 means for preventing movement of said first-named member when a sheet is not fed to the press.

- 11 11. In a throw-out device, a movable slide 25 having a cam projection thereon, means maintaining said slide in a normal path of movement, a fixed jaw, a movable jaw, a member disposed in the path of said cam projection for operating said movable jaw 30 and for varying the path of movement of said slide when said movable jaw cannot be operated, a sheet-feeler having a portion adapted to enter between said jaws in the absence of a sheet, thereby to prevent operation of said movable jaw, and a throw-out 35 actuating member associated with said slide and operated when the path of movement of the latter is varied.

12. In a throw-out device, an abutment, a

movable slide having a cam projection 50 thereon, means normally guiding said slide in a path to clear said abutment, a fixed jaw, a movable jaw, a member disposed in the path of said cam projection for operating said movable jaw and for varying the 55 path of said slide, to cause the latter to engage said abutment, when said movable jaw cannot be operated, a sheet-feeler having a portion adapted to enter between said jaws in the absence of a sheet, thereby to prevent 60 operation of said movable jaw, and a throw-out actuating member operated when said slide engages said abutment.

13. In a throw-out device, a movable slide having a cam projection thereon, means maintaining said slide in a normal path of movement, a movable element, a member disposed in the path of said cam projection for operating said movable element and for varying the path of movement 70 of said slide when said movable element cannot be operated, a sheet-feeler having a portion adapted to enter the path of said element in the absence of a sheet, thereby to prevent operation of said element, and a throw-out actuating member associated with 75 said slide and operated when the path of movement of the latter is varied.

14. In a throw-out device, an abutment, a movable slide having a cam projection 80 thereon, means normally guiding said slide in a path to clear said abutment, a movable element, a member disposed in the path of said cam projection for operating said element and for varying the path of said slide, 85 to cause the latter to engage said abutment, when said element cannot be operated, a sheet-feeler having a portion adapted to enter the path of said element in the absence of a sheet, thereby to prevent operation of said element, and a throw-out actuating member operated when said slide 90 engages said abutment.
